UNITED STATES PATENT OFFICE.

FRED S. ENGLISH, OF NEW LONDON, CONNECTICUT.

CUTTING AND CREEASING PRESS.

Application filed February 3, 1921. Serial No. 442,096.

To all whom it may concern:

Be it known that I, FRED S. ENGLISH, a citizen of the United States, and a resident of the city of New London, county of New London, and State of Connecticut, have invented certain new and useful Improvements in Cutting and Creasing Presses, of which the following is a specification.

My invention relates to a novel jacket device for the impression cylinder of a press on which cutting and creasing of cardboard, etc., is to be done. My invention is adapted to be applied to a printing press for the purpose of converting it for cutting and creasing work, or it may be applied to a press which is specially built only for cutting and creasing.

In cutting and creasing cardboard, as where blanks from which cardboard boxes are to be made are cut and creased, it is customary to make up a form of cutting and creasing rules, in a chase, then mount the chase on the bed of a printing press, and run the sheets of cardboard through the press about the same way as sheets of paper are run through a press when printing. The cutting rules are sharp and cut through the blank sheet whereas the creasing rules are dull and of less height than the cutting rules and they crease the sheet so that it may be readily folded on the crease lines to form a box or other article. For cutting and creasing it is customary to place a hard jacket generally of hardened steel, on the impression cylinder of the press, against which the cutting rules cut the sheets of cardboard. A matrix of heavy stock is generally made up on this jacket as a means against which the creasing rules can press the sheets to crease them.

The present invention relates to the construction of the jacket used for cutting and creasing on presses and to the means for attaching the same to the impression cylinder of the press. One object of my invention is to provide means whereby the jacket may be readily detached at one end and whereby it may be swung upwardly from a pivotal connection at the other end to permit make ready to be inserted between the jacket and the cylinder. The device for securing the rear end of the jacket is quickly detachable and the parts which remain attached to the cylinder will not swing loose or be in the way of the operation of the press when the jacket is removed. It also permits the

rear end of the jacket to be made without a bend and this is important because it is very difficult to make jackets of hardened steel which will not break, where the ends are bent in to be secured to the cylinder. The device at the leading end of the jacket permits the jacket to swing on a pivot, remaining attached to the cylinder while the make ready is being inserted under the jacket, and it also permits the jacket to be quickly and bodily detached from the cylinder and it also permits the leading end of the cylinder to be made without an in-turn or bend.

Another object of my invention is to provide for the insertion of make ready right up to the forward end of the jacket, so that all portions of the jacket are accessible for make ready. Other advantages will be apparent from the detailed description of the invention hereinafter.

In the drawings forming part of this application,

Figure 1 is a side elevation of a press arranged for cutting and creasing,

Figure 2 is a sectional view of the impression cylinder and the jacket, showing the latter in condition for operation,

Figure 3 is a plan view of one corner of the leading end of the jacket and its securing means,

Figure 4 is an enlarged sectional view of part of the cylinder, showing the leading end of the jacket and its securing means,

Figure 5 is a similar view showing the jacket swung up on its pintles to permit make ready to be placed under it,

Figure 6 is an enlarged sectional view showing the rear end of the jacket and its securing means, and

Figure 7 is a plan view thereof.

In Figure 1 I have shown some of the parts of a press for cutting and creasing and in this view I have shown the feed table 1 from which the sheets are fed, the impression cylinder 2, to which my present improvements are applied: the bed 3, the delivery device 4, and the raising and lowering pile table 5 to receive the sheets from the delivery device. The press may comprise an ordinary printing press or it may be a press especially constructed for cutting and creasing, as shown in Figure 1 of the drawings. The present improvements are especially related to or associated with the impression cylinder and this is the only

member of the press proper which is shown in the remaining figures of the drawings.

The cylinder 2 is provided with an impression portion 6 extending partially 5 around it and the removable jacket 13 is applied tightly thereover and the matrix, not shown, is attached to this jacket and is then routed out to correspond with the cutting and scoring rules in the form which is to be 10 used for any particular job.

The jacket 13 is made without end bends; i. e., it is either flat or arched to correspond with the curvature of the cylinder 2 but its ends 10, 11 are not inturned for 15 secured to the impression cylinder as I have provided means for securing the ends in a novel way.

The leading or gripper end 10 of the jacket is shown in Figures 3, 4 and 5 and I will 20 first describe the means for attaching this end of the jacket to the cylinder. The leading end of the jacket is permanently secured to a small section or bar 14 which extends across the leading end of the jacket 25 parallel with the edge. This attachment is preferably made by means of rivets 15 passing through the jacket and the bar 14, although it will be obvious that the jacket and bar may be welded together. If rivets 30 or screws are used, the heads should be countersunk in the jacket as shown herein. To the smaller bar 14 and the jacket there is attached a larger or heavier bar 16, by 35 means of the screws 17, this latter bar also extending across the edge of the jacket. These bars 14 and 16 secured together as if they were one, are adapted to seat in a notch or recess 19 in the forward edge of the impression cylinder, so as to be below 40 or within the circle or arc of the jacket. The bar 16 is provided with a number of apertures which receive therein the dowel pins 20 projecting from the edge 20^a of the cylinder 2. The bar 16 is held engaged on 45 the dowel pins 20 and pressed against the edge of the impression portion of the cylinder 2 by means of clamps 21 secured to the shaft 21^a. The bar 16 is detachably hinged to the cylinder as follows: On each 50 end of the bar 16 there is attached a plate 22 by means of screws 23. This plate has a slot 23^a which fits over a stud 24, the latter being driven into the cylinder, and the construction is duplicated at both sides of the 55 cylinder. A screw 26 passing through one of the jaws of the plate 22 prevents the plate from disengaging from the stud 24 and the slot 23^a is elongated to permit the plate 22 to slide along the stud 24 sufficiently to remove the bar 16 from the dowel 60 pins 20. The jacket may then be swung upwardly on the studs 24 as a hinge, as is shown in Figure 5, to permit make ready to be inserted under the jacket. Or, the jacket 65 may be entirely removed from the cylinder

by turning the screws 26 and releasing the plates 22 from the studs 24. The bars 14 and 16 it will be obvious, are movable with the jacket when the latter is manipulated.

It may be desirable to place make ready 70 right up to the leading edge of the jacket where the sheet grippers 40 engage it, but if the bar 16 were integral with the jacket this could not properly be done, or at least the extreme end of the jacket could not be 75 raised locally crosswise of the cylinder because the bar 16 would be too rigid to adjust itself to local make ready. In the present case the bar 14 is adapted to adjust itself to or is bendable under local make 80 ready as the latter may be inserted between the bar 14 and the bar 16. For this purpose, the screws 17 may be loosened and the make ready may be placed between the bars 14 and 16, to bring the leading end of the jacket 85 up to the required level to suit the rules in the form. This make ready need not be of equal thickness all across the jacket but it may vary locally. When this make ready has been applied, the screws 17 are 90 tightened again.

The device for detachably securing the rear end of the jacket to the cylinder is constructed as follows:

The rear end 11 of the jacket is provided 95 with a number of holes 28 across the jacket and these holes receive therein the heads of the adjustable pins 29. The pin 29 fits and moves in an aperture 41 in the casting 30 which fits over and is held by the shaft 31. There will be a number of these castings, 100 corresponding with the holes 28 in the jacket, all of which are mounted on the shaft 31; and as they are all alike a description of one will answer for all. The castings 30 may revolve loosely on the shaft 31, and they are prevented from shifting lengthwise of the shaft by means of the screws 32, engaging loosely in the circumferential 105 grooves 33 in the shaft. The headed pin 29 is held in the required position by means of a set screw 34 the pin 29 being adjustable in its aperture 41 in the casting. The set screw 34 projects into a circumferential 110 groove 45 in the pin 29 which groove is sufficiently wide to permit for the adjustment of the pin 29, the set screw locking against the bottom of this groove to hold the pin 29 in adjusted position. As the set screw 34 need be turned but slightly to allow 115 for the adjustment of the pin 29 its end always projects into the groove 45 and therefore the pin 29 will not drop out of the casting even when the jacket is removed from the cylinder.

There is a coiled spring 37 for each casting 30 and it surrounds the shaft 31, one end of the spring being anchored in the casting 30 and the other pressing against the edge of the cylinder. The spring 37 tends to 120

swing the casting 30 to the right in Figure 7 or toward the rear edge of the impression portion of the cylinder. The bolt 36, there being one for each casting, is threaded 5 through the casting 30 and its end engages the rear end of the impression portion of the cylinder. To release the rear end of the jacket it is only necessary to slack off the several screws 36, and the springs 37 swing 10 the castings 30 toward the edge of the cylinder. The end of the jacket may then be released from the heads of the several pins 29. When the jacket is replaced, the springs 37 hold the castings 30, in position so that 15 the pins 29 will enter the holes 28. The several screws 36 are then turned and this turns the castings 30 on their shaft 31, moving the pins 29 away from the cylinder edge and thus tightening up the jacket on the cylinder. It is only necessary to manipulate the 20 several screws 36 to attach or release the rear end of jacket. If the cylinder is operated without the jacket there is nothing to interfere with its revolution and there are no 25 loose parts carried by it.

The present device is very economical to make. Another advantage is that when the jacket is removed the parts remain in the 30 position to receive it when the jacket is replaced again. The rear end of the jacket, like the forward end, need not be bent inwardly from the curvature of the remainder of the cylinder.

I have found that when the rear clamps 35 are drawn up tight to tighten the jacket on the cylinder the strip 16 has a tendency to rise up at its forward edge or to rock against the edge 18 of the impression cylinder. To prevent this, I have provided a groove on 40 the forward edge of the strip 16, to form a shoulder 42 and the clamping ends of the tympan clamps 21 are provided with adjustable screws 43 which form what amounts to a hook, to engage over the shoulder 42 and 45 thus prevent the strip 16 from rising at this edge, as well as holding the strip tight on the dowel pins.

Having described my invention, what I claim is:

50 1. In a press the combination with the impression cylinder, of a jacket for the impression portion thereof, a strip secured across the leading edge of the jacket at the inner surface thereof and having its outer 55 surface curved to conform to the curvature of the cylinder surface, a second strip inside said first strip, means for securing said strips together and adapted to permit the strips to be slightly separated to permit 60 make ready to be inserted between the strips.

2. In a press the combination with the impression cylinder, of a jacket for the impression portion thereof, a relatively thin strip secured across the leading edge of the 65 jacket at the inner surface thereof and

adapted to yield locally under the action of make ready and having its outer surface curved to conform to the curvature of the cylinder surface, a second and more rigid strip inside said first strip, means for securing said strips together and adapted to permit the strips to be separated to permit make ready to be inserted between the strips. 70

3. In a press the combination with the impression cylinder, of a jacket for the impression portion thereof, a relatively thin strip secured across the leading edge of the jacket at the inner surface thereof, a second strip inside said first strip, means for securing said strips together and adapted to permit the strips to be partially separated to permit make ready to be inserted between the strips, dowel pins on the cylinder adapted to be received in said second strip, and means 80 for holding said latter strip engaged with said dowel pins. 85

4. In a press the combination with the impression cylinder, of a jacket for the impression portion thereof, a relatively thin strip secured across the leading edge of the jacket at the inner surface thereof, a second strip inside said first strip, means for securing said strips together and adapted to permit the insertion of make ready between said strips, dowel pins on the cylinder 90 adapted to be received in said second strip and hinge supports on which said jacket and its strips are adapted to swing and to slide, whereby the said second strip may be moved into and out of engagement with 95 said dowel pins while engaged with the hinge supports. 100

5. In a press the combination with an impression cylinder, of a jacket for the impression portion thereof, a strip extending crosswise at the leading edge of the jacket, dowel pins in the cylinder adapted to be received in said strip, said strip having a shoulder on the side opposite the dowel pins, and tympan clamps for holding said strip 105 engaged with said dowel pins and arranged to engage over said shoulder of the strip 110 for the purpose set forth.

6. In a press the combination with the impression cylinder, of a jacket for the impression portion thereof, means for securing the leading edge of the jacket to the cylinder, and means for detachably securing the rear edge of the jacket to the cylinder, comprising a shaft, clamps pivoted to 115 swing on said shaft toward and from the end of the impression portion of the cylinder, and headed pins insertible in apertures in the rear end of the jacket and extending into said clamps in a direction substantially radially of the cylinder and means for forcing said clamps in the direction necessary to tighten the jacket on said cylinder. 120 125

7. In a press the combination with the 120

impression cylinder, of a jacket for the impression portion thereof, means for securing the leading edge of the jacket to the cylinder, and means for detachably securing the rear edge of the jacket to the cylinder, comprising a shaft, clamps pivoted to swing independently on said shaft toward and from the end of the impression portion of the cylinder, headed pins insertible in apertures in the rear end of the jacket and extending into said clamps in a direction substantially radially of the cylinder, said pins having grooves therein, set screws in said clamps entering said grooves and engaging said pins to hold them in the clamps, and means for forcing said clamps in the direction necessary to tighten the jacket on said cylinder.

8. In a press the combination with the impression cylinder, of a jacket for the impression portion thereof, means for securing the leading edge of the jacket to the cylinder and means for detachably securing the rear edge of the jacket to the cylinder, comprising a shaft, clamps pivoted to swing on said shaft toward and from the end of the impression portion of the cylinder, springs urging said clamps toward said end of the cylinder and bolts for forcing said clamps away from the cylinder end, headed pins insertible in apertures in the rear end of said jacket and movable in said clamps substantially radially of said cyl-

inder and means for securing said pins in the clamps.

9. In a press the combination with the impression cylinder, of a jacket for the impression portion thereof, a strip secured across the leading edge of the jacket at the inner surface thereof, a second strip inside said first strip, means for securing said strips together and adapted to permit the strips to be slightly separated to permit make ready to be inserted between the strips, and hinge supports connecting said second strip with the cylinder whereby the jacket may be swung on said hinge supports.

10. In a press the combination with the impression cylinder, of a jacket for the impression portion thereof, means for securing the leading edge of the jacket to the cylinder, and means for detachably securing the rear edge of the jacket to the cylinder, comprising a shaft, clamps pivoted to swing on said shaft toward and from the end of the impression portion of the cylinder and having headed pins extending outwardly from said clamps in a direction radially of said cylinder, and means for forcing said clamps in the direction necessary to tighten the jacket on the cylinder.

Signed at New London, in the county of New London and State of Connecticut, this 11th day of January, 1921.

FRED S. ENGLISH.
